(57) **CLAIM**

We claim the original design for a caster support, as shown and described.

DESCRIPTION

FIG. 1 is a left side view of a caster support showing our new design;

FIG. 2 is a right side view thereof;

FIG. 3 is a rear view thereof;

FIG. 4 is a front view thereof;

FIG. 5 is a top view thereof; and,

FIG. 6 is a bottom view thereof.

The broken line showing is for environmental purposes only and does not form a part of the design.
